UNITED STATES PATENT OFFICE.

CHARLES M. ABBOTT, OF WATERTOWN, MASSACHUSETTS, ASSIGNOR TO SAMUEL CABOT, INC., OF BOSTON, MASSACHUSETTS, A CORPORATION OF MASSACHUSETTS.

SHINGLE.

Application filed March 9, 1925. Serial No. 14,129.

In the manufacture of shingles there has been for a long time a demand for a less expensive product having the appearance or effect of the so-called "split" shingle or "shake" shingle, which by reason of its cost of manufacture can only be sold at a price prohibitive to the average builder.

Various attempts have been made to imitate the characteristic appearance of the split shingle, but such on the whole have either been not successful in imitation, or else have been too expensive to meet the demand. These effects have generally been produced by a gouging or rough sawing process, by which the irregularities of the split shingle are approximated.

These irregularities are only a part, and in fact, of less importance than other characteristics of the split shingles. There is another and more important characteristic and one that plays a greater part in the effect of the shingled surface when laid, and especially where the shingles are stained so as to produce the effect of age. The factor underlying this appearance is that of the growth of the material itself. Such shingles are almost always made from the wood of trees of the coniferous family. The wood is generally considered best for shingles is either that of the *Thuya occidentalis* or white cedar, or that of the *Thuya plicata* or red cedar. Such wood is made up of cell structures as true fibre, tracheid, vessel, pith ray, resin duct, etc. In Gymnospermae where vessels and fibres are absent, the late summer wood is composed of radially narrow thick walled tracheids, the wood of the succeeding spring being wide celled and thin walled so that the limit of the year's growth is very well marked. The conifers are the most important family of the Gymnospermae. The shingles are cut in planes radial to the vertical axis of the trunk. This family of trees being of exogenous growth produces alternate rings. In the coniferous family, and particularly in such species as the cedars, the fibro-vascular bundles appear as hard layers alternating with softer tissue. When split on the quarter the cleavage leaves the harder grain in elevation, thus producing a texture or surface which is not only interesting itself, but is well adapted to taking on coloration of either natural or artificial character.

I have found that it is possible to produce this same effect upon a sawed shingle having the ordinary smooth or substantially smooth surface left by the saw. I accomplish this by subjecting the saw shingle to abrasion as by a wire brush or sand-blast or other means. In so doing, I remove to a perceptible depth the soft edge of the layer between the harder fibre of the intervening growth, leaving that growth in a raised bead-like grain which gives a very interesting effect and one very closely approximating the surface effect of the split shingle.

While my invention is by its nature somewhat difficult to illustrate, I have attempted in the accompanying drawings to show diagrammatically at least the principles involved, although obviously I am unable to illustrate the ultimate effect. In the drawings:

Fig. 1 is a diagrammatic section of tree trunk.

Fig. 2 a vertical section on the line 2—2, indicated in Fig. 1.

Fig. 3 is a sectional view showing a wire brush in its action on the surface of a shingle.

Fig. 4 an enlarged section of the treated shingle, and

Fig. 5 a fragmentary plan view of the same.

In these drawings I have indicated at T a theoretical transverse section of a trunk in which the rings R may be taken as representing the annular growths of an exogenous tree. When the trunk is sawed or slit as on the line 2—2, Fig. 1, these rings appear as layers.

As above stated, the wood in the coniferous family, particularly in the cedars, shows strongly its fibro-vascular bundles separated by softer tissue. This gives to the wood a peculiar splitting quality and on cleavage usually leaves the harder fibre in elevation. This I have attempted to illustrate in Figs. 4 and 5. In Fig. 4, which is intended to be a section of wood transverse to the grain, as if a shingle were looked at endwise, the surface is shown as irregularly corrugated by my method. This is conveniently effected by abrasion, as for example, by a rotary wire brush. The strands or wires of such a brush naturally find the softer portions which yield more readily than the harder

portions R. The result is a slight grooving of the softer portions leaving the harder portions R in rounded relief in very close approximation of the natural cleavage of the wood. In this condition the harder fibre is exposed to wear, so that when once treated my shingles have a permanent surface effect which does not vary or which varies only slightly with the passage of time.

In addition to the matter of appearance, my shingles have an advantage over either the split shingle or the gouged or sawed shingle, in that while the surface appears to be rough and uneven, it is in fact substantially a flat surface so that in laying up the shingles the laps are tight and the shingles less liable to become loosened or to be opened to the weather.

20 The method is at once a simple and inexpensive one and shingles can be produced in quantity at a low figure and with apparatus that is simple and yet efficient.

While I have discussed my invention with particular reference to shingles, it will be understood that clapboards or other lumber may be treated in the same manner. The term shingle, therefore is not to be understood as one of limitation, but merely as 30 illustrative of prepared lumber. Moreover, the treatment may be effected by any con-

venient means by which the softer tissue is removed and the harder left in relief. All such variants of my method are therefore to be understood as within the spirit of my 35 invention.

What I therefore claim and desire to secure by Letters Patent is:

1. As a new article of manufacture, a quarter sawed shingle of the wood of a conifer having a surface thereof abraded to remove a portion of the softer layers of the wood while leaving the exposed harder intermediate layers in relief. 40

2. As a new article of manufacture, a quarter sawed shingle of the wood of a conifer having a portion of the softer layers of the wood of a surface thereof removed and the exposed harder intermediate layers left in relief. 45

3. As a new article of manufacture, a sawed shingle of the wood of a conifer having alternate hard and soft rings of growth exposed on the surface thereof, and having the softer growth removed on one surface to expose the harder intermediate layers in relief as longitudinal ridges to give an exposable surface of rift shingle character. 50 55

In testimony whereof I affix my signature.

CHARLES M. ABBOTT.
